(57) **CLAIM**

The ornamental design for an all-terrain vehicle rear fairing, as shown and described.

DESCRIPTION

FIG. 1 is a front-left perspective view of an all-terrain vehicle rear fairing according to our design;

FIG. 2 is a rear-left perspective view thereof;

FIG. 3 is a top view thereof;

FIG. 4 is a left side view thereof;

FIG. 5 is a right side view thereof; and,

FIG. 6 is a rear view thereof.

The broken lines which define the boundaries of the claimed design, and the environment in which the design is used, form no part of the claimed design.

The portions of the all-terrain vehicle rear fairing which are not shown in the drawings form no part of the claimed design.
